Primary Examiner — Sandra Snapp*Assistant Examiner* — Caitlin Mackenzie Williams(74) Attorney, Agent, or Firm — Gibraltar Consulting LLC; Tariq S. Najee-ullah(57) CLAIM

The ornamental design for a bonnet having integrated eyemask as shown and described.

DESCRIPTION

FIG. 1 is a perspective view of a bonnet having integrated eyemask showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a under-side view thereof.

The broken lines in the drawings depict stitching, which forms no part of the claimed design.

1 Claim, 7 Drawing Sheets(56)
